UNITED STATES PATENT OFFICE

JOSEPH O. CADIEUX, OF MERIDEN, CONNECTICUT, ASSIGNOR, BY MESNE ASSIGNMENTS, TO CONNECTICUT TELEPHONE & ELECTRIC CORPORATION, OF MERIDEN, CONNECTICUT, A CORPORATION OF DELAWARE

TELEPHONE-INSTRUMENT SIGNALING

Application filed April 29, 1929. Serial No. 359,123.

My invention relates generally to telephones and more particularly to such constructions adapted for use in apartment houses and the like. The present invention is specifically concerned with the telephone transmitter and signaling device and this application is a partial continuation of my co-pending application Ser. No. 282,102, issued June 11, 1929, as Patent No. 1,717,090, with 10 respect to these features.

One object is to provide a compact, simple and reliable construction which may be embodied in various attractive designs.

Another object is to facilitate construction, assembly and installation.

Another object is to conceal and protect the transmitter.

Another object is to increase the efficiency of the signaling bell or buzzer.

20 Another object is to secure maximum sensitivity of the transmitter.

In the preferred form the apparatus comprises a casing or housing composed of two parts, namely, a back plate or wall member 25 adapted to be secured to the wall and a front plate which supports all the rest of the mechanism and is removable from the back plate. One of these plates, preferably the front plate, has a peripheral flange removably connected to the other plate and laterally surrounding the transmitter, vibrator and electrical connections.

Fig. 1 is a rear view of the part of a telephone instrument embodying my invention, 35 with the rear plate removed.

Fig. 2 is a vertical transverse sectional view of the same but also showing the back plate.

Fig. 3 is a perspective view of the vibrator mechanism.

40 Fig. 4 is a horizontal sectional view showing the vibrator and its support.

The front plate 5 of the casing is preferably formed of molded insulation and is adapted to be secured to the back plate 6 45 preferably by telescoping stud and screw connections 7. The peripheral flange 8 is preferably integral with the front plate and surrounds all of the interior mechanism and connections. The front plate preferably has 50 a flange 9 corresponding to the mouthpiece of

a transmitter and one or more openings 10 leading to the interior.

The diaphragm 11 may be of any suitable construction and is positioned within the flange 12 which projects rearwardly from the front plate around the openings 10. The microphonic device 13 of any suitable construction is connected at its front end with the diaphragm and is supported at the rear by a cross bar 14 which in turn is secured to the flange 12, for instance, by screws 15 at opposite ends. The diaphragm may be yieldingly held in place by spring fingers 16 and 17 which are supported on the flange 12. Electrical connection to the diaphragm and microphonic device may be attained by means of conductor strips 18 and 19.

A signal bell or buzzer member 20 is secured, for instance, by screws 21 to the cross bar 14 and its edge surrounds the flange 12 so that the bell substantially encloses the diaphragm 11 and the microphonic device 13 and thus serves to increase the sensitivity of the transmitter and at the same time produce a maximum loudness of signal of the buzzer or bell as it will be herein termed. It is immaterial to the present invention whether the bell has a musical tone or merely constitutes a noise making device.

The vibrator consists of an electromagnet 22 with a hammer member 23 and suitable contact mechanism. One head of the coil is secured to the front plate by a screw 24. The other head of the coil is integral with the arm 25 which serves as a circuit connection and has a terminal binding screw 26.

The other connection for the coil is from the binding screw 27. These two terminals are arranged alongside of each other and supported in a row on the transverse flange 28 which also supports the connections to the other elements of the device, such as the terminal 29 for push button 30, terminal 31 for the bus bar 32, and so forth. This flange or ledge 28 also supports the plug-in blades such as 33 for connection to the wall sockets. The details of this construction are more fully set forth and claimed in my application #282,102.

10 The stationary contact 34 of the vibrator

is supported by a plate 35 which is secured to a stud 36 embedded or otherwise suitably secured in the rear of the face plate of the casing.

It will be seen from the foregoing that the construction is simple and compact and that it may be readily installed, inspected and repaired. By reason of the arrangement of the parts, the casing can be made quite shallow and as the bell is entirely concealed the casing may be made of any suitable design or material, thus making it entirely feasible to have the telephone instrument harmonize in every way with any scheme of interior decoration or architecture.

It should be understood that any suitable form of microphonic device or its equivalent may be used and other details may be varied within the spirit of my invention.

20 I claim:

1. A telephone comprising a casing having an insulating body, a diaphragm and a microphonic device mounted therein, a signal bell having a flange surrounding said microphonic device and a vibrator for said bell.

2. A telephone comprising a casing having an insulating body with a flange at its rear, a transmitter mounted therein, a signal bell having its rim surrounding said flange and a 30 vibrator for said bell.

3. A telephone comprising a casing, a diaphragm and a microphonic device mounted therein, a signal bell having a flange surrounding said microphonic device and a vibrator for said bell all within said casing.

4. A telephone construction comprising a casing formed of insulating material and having a front wall with an opening and a rearwardly extending flange, a diaphragm supported within said flange, a signal bell having an edge adjacent said flange and a 40 vibrator coacting with said bell.

5. A telephone construction comprising a casing having a front wall with an opening, a rearwardly projecting peripheral flange, and a microphonic device behind the opening, a signal bell having an edge surrounding the microphonic device and a vibrator for the bell located within said peripheral flange.

50 6. A telephone construction comprising a casing having a front wall with an opening, a rearwardly projecting flange, a diaphragm supported within said flange behind said opening, a microphonic device supported by 55 said flange and connected to said diaphragm, a signal bell supported with its flange surrounding the microphonic device and a vibrator for said bell.

7. A telephone construction comprising a 60 casing having an insulating front wall with an opening, a diaphragm and microphonic device supported in rear of said opening, a signal bell surrounding said microphonic device, a vibrator supported at the rear of 65 the wall adjacent the bell and including a

magnet coil, two circuit terminals for said coil mounted side by side on the rear of said wall, one of said terminals supporting said coil.

8. In a telephone, a casing, including a front wall, a circular exteriorly protruding flange on said wall disposed centrally thereof forming a mouthpiece, a circular interiorly protruding flange on said wall concentrically arranged relative to said exterior flange, 70 a diaphragm positioned within said interior flange and spring members for yieldingly holding said diaphragm in position. 75

9. In a telephone instrument, a casing having a sound opening in the front and a flange projecting rearwardly around said opening, a cross bar supported on said flange and a signal bell detachably mounted on said bar substantially concentric with said flange and a vibrator within the casing and coacting 80 with the bell. 85

10. A telephone instrument comprising an insulating casing having a peripheral rear flange and a sound opening in the front of the casing, a cross bar detachably mounted within the casing, a bell supported on said bar behind said opening and a vibrator supported in the casing between said flange and said bell. 90

11. In a telephone instrument, a casing 95 having a sound opening, a flange in the casing alongside of the inner side of the opening, a cross bar supported on said flange and a transmitter and a bell supported on said cross bar within the casing behind said opening, and means for sounding the bell within the casing. 100

12. In a telephone instrument, a casing having a sound opening and a rearward projecting flange, a cross bar supported on said flange, a diaphragm mounted within said flange behind said opening, and a microphone 105 detachably supported by said cross bar and connected to said diaphragm within the casing. 110
